PUNCH PRESS FEEDING DEVICE

Arthur N. Nyquist, Grand Rapids, Mich., assignor to Winters & Crampton Corporation, Granville, Mich., a corporation of Michigan

Application January 21, 1946, Serial No. 642,580

8 Claims. (Cl. 164—87)

This invention relates to a novel and very precise method of determining the weight of the 1 milligram standard.

This invention relates to a novel and very practical control of punch press feeding of material which is to be operated upon in the press.

In punch presses, which utilize a dial feed or other feed equivalent thereto, the automatic movement of the dial or equivalent means on which the work is placed in succession is, in general, by means of a mechanism directly operated by the crank of the punch press. Therefore, the speed of feeding the work is directly dependent upon the speed of the punch press crank and flywheel. As a result when a slowing down of feeding or indexing requires a slowing down of the crank and flywheel connected thereto, the slowing down of feed in general will occur with the heavier articles which are to be worked upon, while smaller and lighter articles may be fed more rapidly and thus the indexing correspondingly stepped up. Therefore, when the indexing is directly controlled and operated by the punch press crank, a slowing down and a diminishing of the stored-up power in the fly wheel occurs under conditions cited above, which limits the work any given punch press can do, depending on the size of the fly wheel.

With my invention the power means for the indexing of a dial or equivalent feed is somewhat separated from the crank and flywheel of the punch press and mechanism is provided for a separate accomplishment of the indexing and the movements of a dial or conveyor feeding means which carries the work, the speed of which is controllable over a wide range to give an operator the necessary time to properly place the work; and at the same time the speed of rotation of the crank and flywheel of the punch press may be made anything desired and that which is best for the particular work which is being done. Furthermore, the dial diameter is theoretically unlimited and can, with proper indexing, be made as large or as small as desired within the range provided on any given punch press.

It is an object and purpose of the present invention to obtain the functions and results above stated in a practical, useful, novel and effective manner. It is further an object of the invention to provide a mechanism for the purposes stated which is operated pneumatically, or may be operated by a combination of pneumatic and hydraulic pressure forces.

In connection with the invention and its practical operation when applied to a punch press and also the dial feed when applied to other machines than punch presses, various safeguarding controls are desirable and, with my invention, are

provided, such as a means to protect the operator by an automatic stopping of the punch press should the operator bring his hand within the range of danger from the descending ram of the press, the hand of the operator under such conditions engaging and moving a shield, the movement of which automatically insures against the punch press ram being tripped and operated until the shield is returned to its protecting position. 10 Further, under circumstances which require it, a kick-out or knock-out mechanism is provided, also pneumatically operated, which ejects or kicks out the finished work after it has been operated upon in the press without the operator being required to remove it. There is also a novel and practical means provided to prevent and stop operation of the ram of the punch press if the dial is improperly indexed. Also positive means 15 for locking the moving dial or other equivalent carrying means for the work is provided to hold such means from movement during the punching operation, and which means is very much less subject to wear and is easier to repair than the conventional means now in use. 20

23 The disclosure made is in connection with
punch presses, but the invention in various parts
of it is not solely limited thereto. For example,
the automatic indexing and movement of the
parts to be processed to proper position, the
30 stopping at such position, the release and move-
ment away after the process has been completed
for another article to be processed to move in
its place, the placing of the articles in the dial
35 or other moving part which carries them and
the safeguarding against injury may have the
constructions accomplishing such objects and pur-
poses applied to many different machines, one
for example a machine for doing drilling work
upon articles. Therefore, while the invention is
40 disclosed applied to one form of machine, it is
not to be limited to punch presses alone.

The objects and purposes recited and others not enumerated and novel construction for the attainment of the same, will appear and be understood from the following description, taken in connection with the accompanying drawings, in which

Fig. 1 is a side elevation illustrating a punch press equipped with my invention in one of its forms.

Fig. 2 is a side elevation of a punch press, the structure being modified to provide an endless conveyor instead of a turning dial or disk carrier for the work to be processed.

55 Fig. 3 is a fragmentary side elevation of the

upper part of the mechanism shown in Fig. 1, at the opposite side of the press.

Fig. 4 is a fragmentary plan, partly in section, illustrating the dial carrier for the work and the means utilized for moving it about a vertical axis.

Fig. 5 is a side elevation thereof, in both Figs. 4 and 5, the protecting shield being shown.

Fig. 6 is a diagrammatic layout of the pneumatic control which is utilized with the invention, as disclosed in Fig. 1, and in which the circuits for compressed air or other pneumatic force are shown.

Fig. 7 is a similar diagrammatic layout of combined pneumatic and hydraulic circuits utilized with the form of invention shown in Fig. 1.

Fig. 8 is a third diagrammatic layout of a pneumatic control utilized when the circular dial or disk work carrier is replaced by an endless conveyor.

Fig. 9 is a plan of the endless conveyor work carrier.

Fig. 10 is a longitudinal vertical section therethrough.

Figs. 11 and 12 are detail views in elevation showing the positive stop mechanism applied to the endless conveyor feed illustrated in Figs. 9 and 10, and

Fig. 13 is a central horizontal section therethrough.

Like reference characters refer to like parts in the different figures of the drawings.

The supporting structure for the punch press may comprise an under support or base 1 and a housing 2 which may be mounted for a pivotal adjustment about a horizontal axis at the front of the machine, such structure in itself being of the environment to which the invention is applied, and not new. A shaft 3 is mounted for rotation at the upper end of the housing and is divided into two parts between its ends in the usual manner with a clutch which may be tripped to connect the two parts for rotation. One end of the shaft 3 in the operation of the machine is continuously driven through a flywheel 4 secured thereto, with a belt 5 around it and around a driving pulley upon the shaft of a motor 6 carried on a bracket 7 secured to the upper housing portion of the machine support. The ram R is reciprocated by the shaft 3 when the clutch is tripped and the two parts of the shaft are connected together. In practice, in punch press machines, the clutch used is of a one revolution automatic throwout type well known in the art so that the ram is moved downwardly and back to its upper position in a single reciprocation of the part of the shaft 3 to which connected, and such reciprocation is secured through either an eccentric or crank connection between the upper end of the ram and the shaft 3. The punch or other tool which is to act upon the work below the lower end of the ram is secured to and extends downwardly from the lower end of the ram in the usual manner.

Underneath the ram a horizontal table 8 is provided, over which a disk-like carrier or dial 9 circular in outline is mounted for rotation about a vertical axis, and may have a plurality of consecutive vertical openings 10 equally spaced, with the centers of all of the openings 10 in a circle of common radius. The circular disk member 9 at its peripheral edge is formed with a channel groove and, at spaced intervals across the groove, vertical pins 11 are secured equal in number to the number of the openings 10 and equally spaced in a sequential series. Above the inner or

rear portion of the table 8 a support 12 is provided either securely connected to the table 8 or formed integral therewith, and which embraces the inner portion of the disk member 9 at its rear and opposed sides.

A dog 13 (Fig. 4) having a substantially semi-circular recess at its free end to conform to a pin 11 is pivotally connected at one end to a slidable bar 15 and is spring actuated so that its free end normally rides against the bottom of the groove in which the pins 11 are located and will, in the rotation of said disk 9 in a counter-clockwise direction (Fig. 4), at its free end pass over said pins in succession. At the opposite side a latching dog 14 is slidably mounted, and at the rear of the disk carrier 9 a bar 15 is slidably mounted in parallelism substantially to the latching or holding dog 14. On the frame extension 12 a second dog 13a is pivotally mounted at one end, and is likewise spring actuated to enter the groove in which the pins 11 are located. It will be apparent that on a movement of the bar 15 to the left (Fig. 4) and with the free end of the dog carried by said bar back of a pin 11 the disk or dial carrier 9 is turned counter-clockwise, provided the holding dog 14 has been moved to the left to permit such movement.

The holding or latching dog 14 is moved by a lever 16 pivotally mounted between its ends and at one end rockably connected with the dog 14. At its other end it passes between two spaced apart pins 17 extending vertically from the bar 15. When the bar 15 (Fig. 4) is moved to the right the dog 13 carried thereby is moved with it, leaves the pin 11 with which it has been previously engaged and rides over the next succeeding pin substantially at the limit of movement of the bar 15 to the right. The pin 17 at the left of the lever 16 engages against it, and moves said lever and withdraws the latching dog 14 which thereupon remains in its withdrawn position until the bar 15 has been moved back to the left to its initial starting position. In such movement to the left the dog 13 carried by the bar 15, pressing at its free end against a pin 11, turns the dial 9 counter-clockwise and to a position such that when the pin 17 at the right of lever 16 comes against said lever, the holding dog 14 will be moved into the path of movement of a pin 11 and prevent turning of the article carrying disk member 9 beyond a predetermined position; and the dog 13a will ride over and be back of another of the pins 11, which hold the member 9 from movement in the opposite direction. Therefore, the article carrying dial 9, at each time that it is turned in periodic step by step movements with the reciprocation of the operating bar 15 therefore, brings an article which is to be processed to a predetermined position underneath the lower end of the ram R, and said dial 9 with said article while it is being processed is securely held against movement, but is freed for movement by withdrawing the holding dog 14 immediately prior to the succeeding reciprocatory movement of the bar 15 which actuates and turns the dial 9.

On a suitable bracket 18 extending upwardly from the support 12, at the side of the machine where the holding dog 14 is mounted, a short horizontal rock shaft 19 is mounted having an arm 20 connected thereto at one end and extending downwardly. At its free end it is connected by a link 21 with a block 22 secured to the upper side of the reciprocating operating bar 15. A second arm 23 is connected to the opposite end of the shaft 19, extends downwardly and

inwardly and has a pivotal connection at its lower end with the upper end of the vertical piston rod 24 which extends downwardly and into a vertical cylinder 25. The piston rod 24 is provided with the usual piston within the cylinder 25 and by entering a pressure fluid alternately into the opposite ends of the cylinder 25, shaft 19 is rocked back and forth and the actuating bar 15 reciprocated. The control of the passage of the pressure fluid to the opposed ends of the cylinder 25 will be hereafter described.

At the center of the disk member 9 a circular hub 26 is located around the center of which the member 9 turns. A vertical post 27 is secured at its lower end to the hub 26 and at the outer edge of the disk a second vertical post 28 is secured on the support 12. Between them a shield 29, substantially rectangular in shape, is mounted on clips 30 which have suitable bearings through the upper ends of the posts 27 and 28 so that the shield may turn about a horizontal axis. The loading of the carrier 9 at the openings 10 therein, with the carrier turning in a counter-clockwise direction, is at the front of said disk. If through any inadvertence the shield is engaged by the hand of the machine attendant it will be at its lower portion and the shield will be turned about such horizontal axis. A bar 31 is secured to the pivot shaft of the outer clip 30, outside of the post 28, and when the shield 29 is located in a vertical position (Fig. 6) the lower end of the bar 31 will engage with and hold a valve in the pressure control conducting system in an open position to permit flow of the pressure fluid used. But if the shield is turned away from its vertical position the arm 31 is disconnected from said valve releasing it to shut off flow of a pressure fluid past it.

A vertical cylinder 32 is disposed underneath the table 8 and has a vertical piston rod 33 extending upwardly through said table, being guided at its upper end therein. Said cylinder 32 is connected with the flow lines or pipes which carry the pressure fluid utilized and, as will be later described, pressure fluid is alternately carried to the upper and lower ends of the cylinder to reciprocate the rod 33. Said rod in its upward movement kicks or knocks out of an opening at 10, the work which has been previously processed by a punch carried by the ram R.

Another cylinder 34 (Figs. 3 and 6) is provided with a piston rod 35 extending therefrom toward the crank shaft of the punch press. The reciprocation of rod 35, in one direction of its movement trips the one revolution clutch so as to connect the two parts of the shafts 3 together for a complete reciprocatory movement of the ram R. As will also be later described, pressure fluid is conducted to the upper end of the cylinder 34 for forcing it in a downward and outward direction (Fig. 3) to trip the clutch, the return of the piston within the cylinder 34 being by reason of its connection to the crank shaft of the punch press.

At the end of the part of the shaft 3, which is periodically turned through one revolution by the continuously driven portion of the shaft through the clutch connection described, a cam 36 is secured having at one side an outwardly extending radially disposed projecting portion 36a as shown in Figs. 1 and 6.

The pressure fluid used in the embodiment of the invention shown in Fig. 1 is compressed air or equivalent compressed gaseous fluid. The compressed air is furnished from any suitable

supply source to and is carried through a pipe conduit 37 which leads to a valve housing 38 in which a piston valve 39 is mounted (Fig. 6) normally acted upon by a spring as shown to move the valve to a position across the entrance end of the pipe 37 into the valve housing. The valve 39 has a rod 40 extending therefrom through the inner end of the housing 38 and which may be supplied with a roller at its outer free end located in the path of movement of the outer end of the reciprocating actuating bar 15. When said bar is at its furthermost limit of travel in one direction, toward the valve housing 38, its end engages against the roller carried by the rod 40 and moves the piston valve 39 against its spring to a position which uncovers the inlet end of the pipe 37 and also uncovers the outlet end of a pipe 41 connected with the housing 38 opposite the end of the pipe 37.

20 The pipe 41 leads to a second valve housing 42 in which a similar piston valve 43, spring actuated in the same manner, is mounted. From the valve 43 a rod 44 extends outwardly in axial alignment with a solenoid winding 45. The 25 armature 46 actuated by the energizing of the solenoid 45 is in alignment with the rod 44. The solenoid when a current passes therethrough, and it is energized, projects its armature 46 against the end of the rod 44 and moves the 30 valve 43 to the position shown in Fig. 6 against its spring to uncover the end of the pipe 41 leading into the housing 42.

Two circuit wires 47 and 48 lead from the opposite ends of the solenoid winding 45, and in one 35 of said wires, for example the one shown at 48, a switch 49 is mounted which is moved to a closed position by a slidably mounted pin 50 and which only is moved so as to close the switch at 49 when a pin 11 comes to it and moves it outwardly. Thus the solenoid will not be energized except with the dial article carrier 9 at a position such that the work which is to be processed, carried at one of the openings 10, is at exactly its right position underneath the ram R. At all other times the switch at 49 is open and the spring 40 acting upon the valve 43 moves the armature 46 into the solenoid 45 with a movement of the piston 45 to a position blocking flow of compressed air through the housing 42 from pipe 41 to an 45 outlet pipe 51 connected at opposite side of the housing 42.

The pipe 51 leads from the valve housing 42 to an additional valve housing 52, having a like piston valve 53 therein, and from which a rod 54 55 extends with a suitable roller or other element at its free end to engage the lower end of the previously described bar 31 connected with the shield 29. When the shield 29 is in its vertical position and the bar 31 in a corresponding position, valve 53 is moved downwardly against its spring, as shown, and the valve is inoperative to obstruct the passage or flow of compressed air through the housing 52 to a pipe 55 which leads from the opposite side of the housing 52 to the upper end of the previously described cylinder 34.

Therefore, with the shield in vertical position the pressure fluid which operates the piston rod 35 to trip the punch press clutch has a free passage to the cylinder 34, but if the shield is turned by inadvertent or other pressure, as by a striking against its lower portion by the hand of the press attendant, the valve at 53 is moved upwardly by its spring to close off passage of compressed air to the cylinder 34, and the punch press clutch cannot be tripped and the press ram

reciprocated until the shield is back in its vertical position.

A branch pipe 56 is connected with the main pneumatic pressure line 37 ahead of the first valve housing 38 (Fig. 6), for conducting compressed air into the main control valve housing 57 within which the main control valve is located. Such main control valve includes a cylindrical intermediate portion 58, at each end of which a shorter and larger diameter collar 59 is located, and beyond each of the collars 59, a second collar 60 of the same diameter is disposed, spaced short distances from the collars 59, and providing continuous annular grooves around the valve between said collars 59 and 60. Between the two inner collars 59 a wide annular groove or space is provided. This main valve is mounted in a cylindrical chamber within the housing 57 and its over-all length is less than the length of such chamber. The interior diameter of the chamber is substantially though very slightly larger than the diameter of the collars 59 and 60.

Substantially midway between the ends of said valve chamber, a port 61 leads from the space between the collars 59 and has branches 62 extending one to each end of the valve chamber, as indicated in dotted lines in Fig. 6. At the opposite side of the housing 57 and interiorly thereof, two recesses 63 are made spaced from each other substantially the same distance apart that the collars 59 are spaced, and from which two pipes 64 and 65 lead one to the upper end of the knock out cylinder 32 and the other to the lower end of said cylinder.

A branch pipe 66 leads to the upper end of the cylinder 25 from the pipe 64. Another branch pipe 67 leads from the pipe 65 to valve housing 68 which is divided by a Z-shaped partition 68a into two chambers, the partition has two openings therethrough, one in a vertical leg of the partition (as shown in Fig. 6) and the other in the horizontal web. The first mentioned opening has associated with it a ball valve 69 yieldingly held in place by a spring, and the other opening is opened to a greater or less degree for the effective passage of compressed air by a screw 70 passing through the upper side of the valve housing and at its inner end reaching to or very closely to the web of the partition. The pipe 67 carries compressed air to one of the chambers of the housing 68, which passes through the ball valve closed opening in the partition, forcing the valve away from the opening, and thence to the lower end of the cylinder 25 through pipe 71. When the air is exhausted from the lower part of the cylinder 25 it must pass through the opening, the area of passage of which is controlled by the screw 70.

From the valve housing 57, two spaced pipes 72 and 73 extend as shown opposite the pipes 64 and 65, joining together to connect with a common pipe 74 which at one side is opened to the outside atmosphere for exhaust purposes, the exhaust being diagrammatically indicated at 75. The opposite end of pipe 74 has two branches 76 and 77 which lead to an additional valve housing 78 having an interior chamber in which a piston valve 79 is located. The branches 76 and 77 connect with the valve chamber at opposite ends thereof so that when the valve 79 is at one end of the chamber it closes passage to one of the pipes 76 or 77, leaving the other open, and when at the opposite end of the chamber closes off the other pipe and opens passage to the one previously closed.

The piston valve 79 is normally held at one end of its chamber in the housing 78, a rod 80 being connected to the valve 79 and extending through the housing and acted upon by a coiled spring 81 to move the valve. In the diagram in Fig. 6, the valve 79 is shown at the lower end of the chamber 78, closing off any passage through branch 76 but with the branch 77 in free communication with the chamber. Rod 80 at its outer end is equipped with a roller which bears against cam 36 and follows it by reason of the spring 81 so that the valve 79 is normally moved by spring 81 to upper position and is forced to lower position when the projecting portion 36a of the cam rides against said roller.

Two pipes 82 and 83 are connected one to each end of the valve housing 57 for communication with the opposed ends of the chamber therewithin. The pipe 82 at its opposite end is connected with the valve housing 78 to communicate with the upper portion with the chamber within it, and the pipe 83 is connected with said housing 78 to communicate with the lower part of such chamber as shown in Fig. 6. The piston valve 79 in lower position is interposed between the end of the branch 76 and the pipe 83. When in its upper position it is between the ends of the pipe 82 and the branch 77.

Operation

With the control exclusively by compressed air or other equivalent gaseous fluid under pressure the parts as diagrammatically shown in Fig. 6 are in the positions to which they have been brought immediately before a tripping of the punch press clutch to operate the ram occurs. In such position the reciprocating bar 15 is moved so as to open the valve 39, a pin 11 on the dial 9 operates the pin 50 to close the switch at 49 thereby opening the valve 43, and the valve 54 is maintained open all of the time that the shield 29 is in vertical position. Accordingly, there is a free passage for compressed air through the main pipe 37 to the cylinder 34 to move rod 35 to trip the clutch. In such initial position the piston in cylinder 25 is at the lower end of the cylinder and similarly the piston in cylinder 32 is at its lower end. There is a clear exhaust line for air from below the piston in cylinder 25 through the pipe 11 past the opening controlled by screw valve 70, through the pipe 67 to the pipe 65; pipe 65 is directly connected to the lower end of cylinder 32 for exhaust therefrom. The exhaust air, therefore, from the lower parts of both cylinders enters the valve housing 57 between the collars 59 and 60 at the right, and passes out through the branch 73 and is thence exhausted at 75. It is also apparent that with the valve 79 in its lower position, as shown in Fig. 6, there is a line of connection from the left hand end of the chamber in the housing 57 through the pipe 82, thence through the housing 78 and pipe 77 to the exhaust; and there being a pressure connection through the port 61 and the branch 62 at the right compressed air at the right hand end of the valve within the casing 57 moves said valve to the position shown.

In the position of such valve as shown, compressed air through the branch 56 is directed through the pipe 64 and its branch 66 to the upper ends of cylinders 25 and 32, moving them downwardly and forcing the air below the pistons 25 and 32 outwardly through the exhaust at 75, to carry the reciprocating bar 15 to the left to open the valve 39 which, whenever the reciprocating

bar 15 is away therefrom, is in closed position. Upon the punch press clutch being tripped, the cam at 36 moves to release rod 80 and valve 79. Valve 79 moves to its upper position uncovering the inner ends of pipes 76 and 83, thereby connecting the pipe 83 with the exhaust and closing the pipe 82 at its end where connected to the housing 78. Thereupon the compressed air conducted through the branch 56, port 61, to the branch 62 at the left and into the chamber of the housing 57 at the left hand end of the valve, moves it to the opposite end of the chamber, closing off the recess at 63 at the left by the adjacent collar 59 so that compressed air cannot pass through the pipes 64, but instead passes through the pipe 65 and its branches, whereupon the pistons in cylinders 25 and 32 are moved upwardly, and the exhaust air in said cylinders above said pistons passes through the pipe 64 and its branch 66 and through the pipe at 72 to the exhaust. This moves the actuating bar 15 to the right away from the valve 39, releasing said valve, and moving bar 15 to a position where the actuating dog 13 carried by it is brought behind the next succeeding pin 11, and the holding or locking dog 14 (Fig. 4) is withdrawn to permit a turning of the dial 9 upon the return of the actuating bar to its extreme position to the left in Fig. 6, a simultaneous return of the holding dog 14 to its operative position.

There is thus provided a periodic step by step turning movement of the dial 9 automatically occurring at regularly timed intervals. The time is controlled by the position of the screw 70 with respect to the opening through the partitions 68a, the time passage of air through such opening being controlled by the position of the screw. The upward movements of the pistons in both cylinders 25 and 32 is rapid, being unchecked except by what back pressure may be generated in the pipes and passages leading from the upper ends of said cylinders to the exhaust, therefore the movement of the reciprocating bar 15 to the right (Fig. 4) is rapid. But the return movement of said reciprocating bar controlled by the piston in cylinder 25 may be either controlled to any speed between a maximum and minimum, dependent upon the rapidity of exhaustion of air from below the piston in cylinder 25 through the partition at 68. Thus the movement of the dial is controllable within a wide range of speeds of turning movement, permitting such turning to be controlled in accordance with the time required to load the dial with the articles which are to be processed. The knock-out or kick-out movement, both in its upward working stroke and its downward return stroke, is not checked and both reciprocatory movements of the rod 33 are at substantially the same speed.

The driving of the flywheel by the motor is separately and independently controlled as to speed by controlling the speed of the motor without reference to the dial operation.

If, as previously described, the valve 53 is released by moving the shield 29 out of its vertical position, the ram of the punch press cannot be connected with the power which operates it until the shield is returned. And if the dial is not moved to a proper position to bring an article which is to be processed directly at its required position underneath the die carried by the ram, then the valve 43 closes off the passage of air to the cylinder 34 and the press will not operate. As soon as the clutch is tripped and the proper connection made between the power and

the ram the release of valve 79 causes, as described, the movement of the dial actuating bar 15 away from the valve 39, so that it closes off passage of compressed air to the cylinder 34 and the press clutch cannot be again tripped until the valve 39, and also valve 43 are moved to open positions as in Fig. 6. A stopping of the machine operation of course may be obtained by shutting off the supply of compressed air to the pipe 37.

10 The control of the dial movement is not necessarily restricted to the use of pneumatic pressure but, as diagrammatically shown in Fig. 7, a combined pneumatic and hydraulic operation may be used. The tripping of the clutch through 15 the rod 35 with the valves in the housings 38, 42 and 52 open is by compressed air or other equivalent compressed gaseous fluid passing through the pipe 37 and through the several pipes 41, 51 and 55 when, as controlled by the turning of cam 20 36, the valves named are all in open position.

The operation of the main control valve within the housing 57 is by means of a closed hydraulic circuit, and the operation of the pistons in cylinders 25 and 32 is by a liquid under pressure instead of compressed air. Some modification in structure of the control valves is made. For example, the main valve within the chamber of housing 57 has its intermediate and end collars 59 and 60 spaced substantially equal distances 30 apart. The valve within the upper valve housing 78 is of a modified construction having a lower head 84 and an upper collar 85 spaced therefrom, with rod 80 extending outwardly and actuated by the spring 81 as previously described, 35 the roller at the upper end of rod 80 riding against cam 36. The pipes 83 and 82 where connected to the valve housing 78 are connected by two forks or branches 86 and 87 respectively, the entrance ends being spaced short distances from each other. A pipe 88 connects the lower end 40 of the chamber of the housing 78 directly with the intermediate chamber between collars 59 within the control valve housing 57. The pipes 64 and 65 are branched or forked where they are 45 connected with the lower side of the housing 57 as shown at 89 and 90.

A conducting pipe 91 is connected with the housing 78 at its upper end to communicate with the chamber therein above the collar 85, and at 50 its other end is connected to a main liquid pressure supply pipe 92 which, at one end, connects to the pipe 88 previously described and at its other end is connected with a pump 93, the housing of which has an intake pipe 94 in connection with an oil supply tank or sump 95. The oil is 55 pumped from the tank 95 and forced through pipe 92 as indicated by the arrow. Return of the oil or other liquid used to the tank 95 is through a pipe 96 which has a fork or two branches 97 at its end where it connects with valve housing 60 above the forks 87 of the pipe 82. A branch 98 joins with the pipe 96 and has two leads or branches therefrom extending to the valve housing 57, in communication with the chambers between the end collars 60 and the intermediate collars 59 of the main control valve. The pipes 64 and 65 connect with opposite ends of the cylinder 32 and a branch pipe 66 from the pipe 64 connects with the upper end of the cylinder 25 70 with a branch pipe 67, valve housing 68 with ball and manually operated screw valve 70 therein, and pipe 71 being associated and connected with the lower end of the cylinder 25.

With the parts in the position shown in Fig. 7, the liquid under pressure produced by the pump

93 is forced through the pipe 92 to pipe 88 and to the branch 94 above the valve in the housing 78, and to the central chamber between the collars 59 in the housing 57. Also oil under pressure is directed at the upper end of the pipe 88 into the lower end of the housing 78 against the lower piston 84. Such oil under pressure passes out of the housing 57 into the pipe 64 and its branch 66 to the upper ends of the pistons 25 and 32. The main control valve within the casing 57 has been moved to the left by oil pressure through the pipe 91 and thence through the pipe 83, and oil at the opposite end of the main control valve has been exhausted from the housing 57 through pipe 82 to the annular space between the piston 84 and collar 85 and thence outwardly through the return pipe 96 by reason of the lower branch or fork at 97, the oil flowing from the pipe 82 through its upper branch 87. When the valve within the housing 78 is released by the movement of the projection 36a of cam 36, oil will pass from the pipe 92 into the pipe 88 and thence upwardly into the lower end of cylinder 78 therefrom through the lower branch of pipe 82 and against the left end of the main control valve, while the oil in the chamber at the right end of the main control valve will be forced outwardly through pipe 83, the branch 86 and thence through the upper branch of the pipe 96.

With the main control valve in the position shown in Fig. 7, and with oil or other hydraulic liquid forced into the upper end of cylinders 25 or 32, oil below the pistons therein will be forced out through the pipe 65 and the connection including the pipe 67, 71 and valve housing 63 into the chamber at the left between collars 59 and 60 and exhausted through the pipe 98 and its branch 100 to return pipe 96.

When the valve 58 is moved over to the other end of the housing 57, that is, to the right, connection between the pressure line 92 and the pipe 64 is broken or closed off, and is opened with the pipe 65, whereupon the liquid under pressure is conducted to the lower end of the cylinders 25 and 32 with an upward movement of the pistons therein and an exhaust of liquid above said pistons through the pipe 64 and branch 66. The exhaust oil will pass through the left hand branch pipe at 89 into the chamber at the left between collars 59 and 60 and thence through pipes 98 and 99 and the main return pipe line 96.

The turning operation of the dial in step by step periodic movement and with the control of the time, also the operation of the knock-out or kick-out rod are the same as with the full pneumatic construction previously described. The hydraulic circuit is a closed circuit and there is a saving of compressed air and in some respects the hydraulic operation of turning the dial is of a more assured and smoother character. The principle of operation and the mechanism in general are very similar.

In Figs. 2, 8, 9 and 10, the circular dial for carrying the article to be processed and a step by step turning thereof, is replaced by an endless conveyor, with a step by step movement of the conveyor.

Over a table 101 (Fig. 10), the upper run of an endless conveyor 102 passes from front to rear around spaced upper idle sprockets 103 and 104 and a rear lower drive sprocket 105. A plurality of transverse plates 106 each with an opening at 107, for the same purposes as the openings 10 in the dial 9, are connected in succession to the conveyor chain being secured to spaced lugs 108 extending outwardly from the conveyor. Directly underneath the ram R and the punching die carried thereby is a base 109 mounted upon the table 101. Each of the plates 106 midway its side edges and at one side has a triangular notch 110 therein. The shield 29 is mounted to turn about a horizontal axis on posts 27 and 28 carried by the table 101 (Fig. 9). The guards at 111 and 112 cover the rear and front portions of the upper run of the conveyor and the front portion of the lower run thereof to protect the punch press attendant from injury.

A cylinder 113 (Fig. 2) has a piston therein with a piston rod 114 extending outwardly at its upper end and connecting at its free end with an arm 115 which, through a suitable one-way operating clutch mechanism, including a driving dog 116 and spaced pins 117, turns the driving sprocket 105 in periodic step by step movements on the upper reciprocation movements of rod 114, moving the sprocket chain upon the outward movement of the rod 114. The clutch is of an overrunning character so that there is no movement of the driving sprocket upon retraction of the rod 114.

The housing 38, within which the piston valve 39 is mounted, has the rod 40 connected with the valve therein interposed in the path of movement of the arm 115 when it is moved to its uppermost position to thereby open the valve, the same as the reciprocating bar 15 opens it in the previously described structure at one extreme of its movement. The switch at 49 controlling the solenoid 45 is in an operative position only when a notch 110 on an article holding plate 106 arrives at a proper position in which the article held by the plate is directly underneath the processing punch therefor. The shield 29 has connected with one of its trunnions a horizontal arm 118 (Fig. 8) to hold the valve within the housing 52 in open position. Inasmuch as the movement of the article carrying plates 106 with the conveyor will carry the finished or processed articles to the rear and automatically disengage them through gravity, the knock-out cylinder is not needed.

The diagram shown in Fig. 8 is substantially the same as that shown in Fig. 6 with the knock-out for the finished work eliminated, and with the step by step operation of the endless chain conveyor instead of an equivalent step by step turning movement of the dial 9. It is not necessary to repeat the operation of the control valves as there is identity with those previously described in connection with the structure and diagram appearing in Fig. 6.

The endless chain conveyor type of structure may be subject to extension and lost motion because of wear at the pivots of the connected links which may bring the openings at 107 to slightly inaccurate positions with respect to the ram of the press, therefore, the punch carried by the ram may have its downward stroke out of proper alignment with the work which it is to process below it. To compensate and correct anything of this nature which may occur, pointed pins 118 shown in Fig. 10 may be connected to and extend downwardly from the lower end of the ram for entrance into suitable openings 119 in the plates 106. The pins accordingly will properly locate and orient the plates if not in proper position, so that bad or destructive work upon the work which is being processed is safeguarded or insure against.

Another factor in conjunction with the endless conveyor type of construction shown in Figs. 9 and 10, is concerned with the momentum attained in the movement, which unless a very positive stop is provided may carry a plate 106, coming underneath the ram of the press, to a position in advance of where it should have stopped. In Figs. 11 to 13 inclusive the structure to insure the positive stop for such conveyor is shown. The sprocket wheel 105 is bolted at the inner side 10 of a cylindrical annularly grooved disk member 120, across the groove of which the spaced pins 117 are located. Said member 120 is keyed to a horizontal shaft 121 extending between and mounted at its ends in the sides 1 of the supporting frame structure for the machine. Member 120 has an extended hub or sleeve 120a at its outer side which passes loosely through the bottom of a cup shaped housing 122 which houses the member 120 within it and which carries the operating dog 116 to successively engage with the pins 117.

A ratchet wheel 123 is keyed to the projecting sleeve 120a, turning with it. The housing 122 has the operating arm 115 which is rocked by the reciprocating piston rod 114, integral therewith or permanently connected. A pin 124 extends outwardly from the bottom of the housing member 122 and is rocked through an arc of a circle from the position shown in Fig. 11 to that shown in Fig. 12, being returned to the lower position at the end of a complete reciprocation of the piston rod 114.

On a suitable supporting bracket 125 which is carried on the machine frame 1 a dog 126 is pivotally mounted, normally actuated by a tension spring 127 so as to engage with the ratchet wheel 123.

On the movement of the piston rod 114 into the cylinder 113 (Fig. 2), the housing member 122 is rocked to move the dog 116 from one pin 117 to the next succeeding pin (Fig. 10) moving in a counter-clockwise direction. The dog 126 is engaged with a ratchet wheel 123 whereby the endless conveyor described remains motionless. A short time before the extreme of such movement of the piston rod 114 is reached, the pin 124 will come against the under side of dog 126 (Fig. 12), lifting it to disengaging position so that on the return or upward reciprocatory movement of rod 114 and a rotation of the disk member 120 and sprocket wheel 105 connected therewith in a clockwise direction, caused by dog 116 pushing against the next succeeding pin 117, the ratchet 123 is free for movement and may turn to move the tooth which has previously been engaged by the stop dog 126 underneath such dog, this occurring before pin 124 moves far enough away from the dog 126 in a clockwise direction to lower the dog to its operative position. Such movement of the pin 124 however will occur before the return of the upwardly and outwardly reciprocatory movement of the rod 114 is completed and dog 126, therefore, will be interposed in the path of movement of the next succeeding tooth of the ratchet wheel 123, stopping said wheel and the parts connected and governed by its movement, including the endless conveyor, at proper position.

The structure described is very practical and useful and with it a long desired control of the feeding of articles to an automatic punch press, independent of the power means used to drive it, has been attained with the many beneficial results which have been outlined and described.

As earlier mentioned, while the invention has been disclosed as of great utility in conjunction with automatic punch presses, the automatic feed of a dial type article carrying table, or of an endless article carrying conveyor, and their stopping at proper positions, with the numerous safeguards described, is not restricted solely to punch presses but is of great utility in many other relations. Work which is to be processed by drilling in a drill press may be carried to the drilling station in the same manner, operated either by pneumatic or combined hydraulic and pneumatic means, the operator of the machine safeguarded against injury, the drill being brought to the work at the processing station of the machine similar to the movement of the punch in the punch press toward and into processing engagement with the work which it is to act upon. Therefore, the invention is not restricted to the one type of machine disclosed but, is to be considered comprehensive of all forms of structure coming within the scope of the appended claims defining the invention.

I claim:

1. In a construction as described, a horizontal support, a carrying member mounted for movement thereover, said carrying member having equally spaced means for the detachable carrying of articles to be processed, a cylinder, a piston rod extending from one end thereof, fluid means for reciprocating said rod, means interposed between said piston rod and said movable member for moving the member a predetermined distance, equal to the distances the articles carried by member are spaced, upon movement of said piston rod in one direction, said article carrying member remaining at rest on movement of the piston rod in the opposite direction, means for stopping said article carrying member at the completion of each movement thereof to accurately position articles carried thereby successively at a predetermined processing position, a processing member mounted for vertical up and down movements at said predetermined position to process the articles in succession at such predetermined position, conducting means for carrying pressure fluid to opposite ends of the cylinder, means for actuating said processing member in a downward direction followed by a return to an upper position, pressure fluid actuated means for tripping said last mentioned means to render it operative upon retraction of the piston rod into said cylinder and after an article has been moved to said predetermined position of processing, and means for automatically reversing the flow of pressure fluid from one end to the other of said cylinder rendered operative by the means actuating said processing member.
2. A construction as defined in claim 1, and means obstructing the conducting means for pressure fluid to said tripping means, except when the article carrying means has been moved to carry an article thereon to said predetermined processing position, and freeing for passage of said pressure fluid when the article carrying means is at said position.
3. In combination, a horizontal support, a horizontal dial mounted on said support to turn about a vertical axis, said dial at equally spaced distances from its axis having a plurality of equally spaced article receiving stations, fluid pressure operated means for periodically moving the dial about its axis a distance equal to the spaces between articles carried thereby, said fluid

pressure means including conducting pipes, a power driven processing member normally at rest and adapted to be trip connected with power driving means; therefor, fluid pressure operated means for trip connecting said processing means with said driving means, articles carried by said dial being brought successively to a processing position for operation thereon by said processing means, a valve in the pipe leading to said trip means, means normally closing said valve to obstruct the pipe and means carried by the dial moving said valve to open position only at the times when an article has been moved to a predetermined position with relation to said processing means for processing thereby.

4. A machine having a horizontal table, a horizontal carrying member mounted to move over the table having a plurality of equally spaced article receiving stations, at each of which an article to be processed may be detachably connected with said member, a cylinder, pipes for conducting fluid pressure to opposite ends of the cylinder, a piston rod extending through one end of the cylinder and movable inward or outward as fluid pressure is conducted to one end or the other of said cylinder, means interposed between said piston rod and the movable carrying member for moving said article carrying member upon longitudinal movement of the piston rod in one direction, said article carrying member remaining at rest on movement of the piston rod in the opposite direction, processing means movably mounted over said article carrying member underneath which articles carried by said carrying member successively pass and stop each at a predetermined position for processing operation thereupon, said processing member being normally at rest, a continuously operative driving means, therefor, means for periodically connecting said driving means to actuate said processing member, valve means for reversing the flow of pressure from one end of the cylinder to the other, and means for operating said valve means in synchronism with the operation of said process member.

5. In combination, a movably mounted carrying member having a continuous series of equally spaced means for the detachable connection of articles to be processed on said carrying member, a cylinder, a piston rod reciprocable in the direction of the length of the cylinder extending through one end thereof, means actuated by said piston rod for moving said carrier member a distance equal to the spaces between said article holding means on said carrier member, means for alternatively conducting a pressure fluid to opposite ends of the cylinder, including conducting pipes the flow of fluid through one of which will move said piston rod outwardly and through the other inwardly, valve means in one of said pipes permitting free flow of pressure fluid to said cylinder but regulating and restricting exhaust flow of fluid from the cylinder whereby the time elapsing between movements of said carrier member may be selectively increased or decreased.

6. A construction as defined in claim 5 and automatic valve means for reversing the flow of liquid to said cylinder at opposite ends thereof.

7. In combination, a movably mounted carrying member having a continuous series of indi-

vidual article connecting stations equally spaced from each other, at each of which an article may be detachably connected, a cylinder, pipes for carrying pressure fluid connected at opposite ends of the cylinder, a piston rod reciprocably mounted and extending through one end of said cylinder, means interposed between the piston rod and said carrying member for moving said carrying member the distance of a space between each of said stations on the carrier member on movement of the rod in one direction, said carrier member remaining at rest when the rod is moving in the opposite direction, and adjustable valve means interposed in one of said pipes to control the movement of said rod in said one direction to thereby govern the length of time of the return of movement of said rod.

8. In combination, a punch press having a horizontal table, a movable article carrying member mounted to move over said horizontal table, said member having a plurality of equally spaced article receiving stations for carrying articles to be processed, means for periodically moving said article carrying member a predetermined distance to bring each of the articles carried by said member to a predetermined position at which it may be operated on by the punch press, a vertical ram adapted to carry a tool for processing said articles in succession, driving means normally disconnected from the ram, fluid pressure operated means for trip connecting said driving means with the ram to thereby reciprocate said ram, means for rendering said tripping means inoperative, except when an article carried by the article carrying member is accurately positioned underneath the ram for processing by the tool thereby, a shaft with which said ram is connected for reciprocating said ram upon rotation of the shaft, said trip means upon actuation thereof, connecting said driving means with the shaft to turn it, said means for periodically moving the article moving member including, a cylinder, a piston rod extending outwardly at one end of the cylinder, means for conducting fluid pressure connected with each end of the cylinder, an automatic valve, and means actuated by the rotation of said shaft for controlling said automatic valve for reversing the flow of pressure fluid from one end of said cylinder to the other as an article carried by said article carrying member is processed.
